US0D1104810S

(12) **United States Design Patent** (10) Patent No.: **US D1,104,810 S**
(45) Date of Patent: ** Dec. 9, 2025

(54) **CONTROLLER**

(71) Applicant: **Dometic Sweden AB**, Solna (SE)

(72) Inventors: **Eric Schuh**, Stevensville, MI (US);
Clayton Hendry Meyers, Paw Paw, MI (US); **Samuele Meda**, Chichester (GB);
Jens Nybacka, Nacka (SE)

(57) **CLAIM**

The ornamental design for a controller as shown and described.

DESCRIPTION

FIG. 1 is a perspective view of a controller, showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

In the drawings, the broken lines depict portions of the controller that form no part of the claimed design.

1 Claim, 5 Drawing Sheets
